UNITED STATES PATENT OFFICE.

LUDWIG DÜRR, OF FRIEDRICHSHAFEN, BODENSEE, GERMANY, ASSIGNOR TO LUFT-SCHIFFBAU ZEPPELIN GESELLSCHAFT MIT BESCHRANKTER HAFTUNG, OF FRIEDRICHSHAFEN, BODENSEE, GERMANY.

OUTER COVER OF AIRSHIPS.

Application filed January 9, 1925, Serial No. 1,399, and in Germany February 11, 1924.

My invention relates to the outer cover of airships, especially of those of the rigid type. The frame-work of such ships is surrounded with a fabric cover. The object 5 of such cover is to give the ship a smooth outer surface which is important with regard to the air resistance. For the purpose of further reducing the air resistance a coating of varnish is generally applied. 10 Such varnishing renders the cover practically impermeable to air. The same effect will occur if, for instance, a metal cover were used. When the airship is in flight, there will be portions in the outer cover 15 where the air pressure from the inside and that from the outside will not be in equilibrium. This will depend on the shape of the airship body moving through the air. Increased pressure from the outside will 20 especially be created when the ship is descending from a higher altitude. Also the cowls on the openings for gas escape which are shaped to create a vacuum effect, will cause a decreased pressure inside the outer cover. Such low pressure inside the ship 25 may easily cause a rip in the outer cover or even have a bad effect on the hull structure inside.

My invention does away with this danger 30 by providing adequate openings in the outer cover by which air may automatically flow into the space confined by the cover and thereby prevent a substantial decrease of pressure inside. I prefer to have such openings in the lower forward part of the airship. A very good way of providing such 35 automatically operating openings is to substitute portions of the outer cover by wide woven fabric. This will allow a smooth and easy way of equalizing the pressure inside 40 and outside of the cover. Of course, adequate slits in the cover will have a somewhat similar effect, as well as openings which will be closed under normal conditions and 45 open only when a certain decrease of pressure inside is attained.

Having explained my invention in general, I will now point it out in detail referring to the drawing which represents some examples embodying my invention. 50

Fig. 1 is a longitudinal section through the bow of the airship, and Fig. 2 is the corresponding side view.

The outer cover of the airship is designated by the letter *a*. The hull structure is 55 not shown, except that the structure of a gangway is indicated at *l*. There is a clearance between the gas cells *b* and the outer cover. Gas passages *m* lead to cowls *g* 60 which are here shown at the top.

In Fig. 2 a portion *h* of the outer cover *a* is made of wide woven fabric, so as to be permeable to air and to allow of an interchange between the air inside the cover *a* and the outside air. 65

Slits *i* in the outer cover *a* may serve the same purpose.

The described openings in the outer cover may be situated at any suitable place, but I prefer to have them in the lower part of 70 the ship's bow. They will then operate easily and serve the purpose best.

I want it understood that I do not limit myself to the examples described or shown in the drawing, as many variations will 75 occur to people skilled in the art.

What I claim is:—

1. In a rigid airship an outer cover substantially impermeable to air, a portion of said cover being replaced by wide woven air-permeable fabric adapted to regulate difference in pressure occurring between the air outside and the air inside of said cover. 80
2. In a rigid airship, an outer cover substantially impermeable to air, a portion of said cover being replaced by a structure permeable to air but adapted substantially to continue the surface line of the ship, whereby air resistance is maintained at a minimum. 85
